UNITED STATES PATENT OFFICE.

JESSE G. COOMBS, OF MILLVILLE, NEW JERSEY.

IMPROVEMENT IN COMPOUNDS FOR COUGH-SIRUP.

Specification forming part of Letters Patent No. **153,933**, dated August 11, 1874; application filed June 6, 1874.

To all whom it may concern:

Be it known that I, JESSE G. COOMBS, of Millville, Cumberland county, New Jersey, have invented a new and Improved Compound for Cough-Sirup, of which the following is a specification:

My improved compound for cough-sirup consists of tincture of lobelia, one-half ounce; tincture of myrrh, one-half ounce; tincture of capsicum, one-fourth ounce; tincture of blood-root, one-fourth ounce; alcohol, one and one-half ounce; oil of anise, one-eighth ounce; winter-green, one-eighth ounce. Mixed in one pint of molasses.

The proportions may be varied to some extent.

DOSE.—A tea-spoonful whenever the cough is troublesome; also, before going to bed. Shake the bottle well before taking.

Having thus described my invention, I claim as new and desire to secure by Letters Patent—

A compound formed of winter-green and capsicum mixed in molasses with alcohol, blood-root, myrrh, and oil of anise, substantially as and for the purpose specified.

J. G. COOMBS.
